UNITED STATES PATENT OFFICE.

ROBERT W. BARKER, OF PATERSON, NEW JERSEY.

AUTOMATIC WOOD-TURNING MACHINE.

SPECIFICATION forming part of Letters Patent No. 723,809, dated March 31, 1903.

Application filed November 17, 1902. Serial No. 131,625. (No model.)

To all whom it may concern:

Be it known that I, ROBERT W. BARKER, a citizen of the United States, residing at Paterson, in the county of Passaic and State of

5 New Jersey, have invented certain new and useful Improvements in Automatic Wood-Turning Machines, of which the following is a specification, reference being had therein to the accompanying drawings.

10 This invention relates to machines for cutting and shaping wood and other material, and particularly to that class of machines in which revolving and horizontally-moving cutters are employed to shape the material as it 15 is automatically fed from a hopper.

The construction and advantages of my machine will be hereinafter set forth, reference being had to the accompanying drawings, in which—

20 Figure 1 is a front elevation of the machine; Fig. 2, a top plan view; Fig. 3, an enlarged detail view, partly in section, of the carriage-moving device; Fig. 4, a sectional view of a portion of the machine on the line A A in Fig. 25 1. Figs. 5, 6, and 7 illustrate the results or product of the various operations of the machine; Fig. 8, an end view; Fig. 9, a view, partly in section, showing the device for moving the carriage; Fig. 10, another end view; 30 Fig. 11, a cross-sectional view of the carriage on the line B B in Fig. 14; Fig. 12, an end elevation of the carriage; Fig. 13, a back view of same; Fig. 14, a sectional view of the carriage on the line C C in Fig. 16; Fig. 15, 35 a front view of the carriage, and Fig. 16 a top plan view thereof.

One object of my invention is to do with one machine what is ordinarily accomplished partly by hand and by two or more machines 40 in the turning of spools or bobbins, and particularly quills. To automatically feed the blocks of material from a hopper to the spindles, which receive and rotate them to be operated upon by revolving cutters and fixed 45 knives carried by a horizontally-moving table or carriage during the different stages of the turning until the block of wood has been delivered from the machine a completely-turned quill, is another object sought for and 50 accomplished by my machine; and a further object of my invention is to produce a simple, effective, durable, and inexpensive labor-

saving machine that will require but little attention and that will produce with facility larger results than are produced by the machines now in vogue. 55

Referring to the drawings, 1 is the main supporting - frame, having a table 1^a, upon which is secured the support 2 for the mechanism 7, that operates the spindle 4 and the support 3 for the sliding spindle 5 and its turning device 6.

The blocks D, with an opening d, are placed in the hopper 75 and are fed to the ends 8 and 9 of the spindles 4 and 5, as will as hereinafter fully set forth. On the end 9 of the spindle 5 are teeth 10, which engage indentures in the end of the block and cause it to rotate. A drive-shaft 11 is journaled in the frame 1 and is driven from the pulleys 13 60 through the operative gear connections 12 12^a, the latter of which is mounted upon the short shaft 14. A cam 15, provided on its high point with a guide 16 and provided also with an extended sleeve 17 in conjunction with 65 the lever 18^a and the connecting-rod 18, which is pivotally secured thereto at 18^a by pin 18^e and is provided with a guide 18^b, having a roller 19, which is engaged by the cam-guide 16, constitute the mechanism which give the 70 traveling motion to the carriage 34. The lower end of the lever 18^a is pivotally secured in the bracket 18^d in the frame 1, and its upper end is connected to the carriage-lugs 35 by the rod 36, and said lever being operated 75 by the cam 15 through the connecting-rod 18 the carriage is caused to travel back and forth on the support 33.

The spindle 5 is given a sliding lateral movement in order to insert it in and withdraw it 80 from the opening in the end of the block D at the proper time—that is to say, when the block is delivered from the hopper and when the quill is completed. This is accomplished by 85 a dish-shaped cam 21, the flange or edge of which varies in height or is broken away, as is indicated by 22 in Fig. 10, said cam being secured to the end of the shaft 11; a lever 23, fulcrumed in a support 24 on the frame and having at its lower end a roller 25, adapted 90 to contact with and roll upon the irregular edge of the cam 21 to operate the lever and cause the bifurcated upper end 27 thereof and the collar 28 which is loose on the spindle 5 95 100

between the fixed collars 29 and 30, to give the rotating spindle 5 a longitudinal movement, as stated. To facilitate the said motions of the spindle 5, ball-bearings may be 5 provided at 31 between the collars on the end of said spindle.

On the lower end of the lever 23 is a stud 32^a, and said stud is connected with the frame 1 by a spring 32, which tends to hold the roller 10 25 in contact with the edge or irregular flange of the cam 21, thus regulating the longitudinal movement of the spindle 5. Secured to the carriage 34 are adjustable bearings 40 41, having adjusting-slots 42, the adjustment of 15 said bearings being regulated by the rod 43 and the set-screws 52. The rotary cutter 47, provided with knives 48, is mounted on the shaft 44, which is journaled in the said bearings 40 41, which are in turn secured to the 20 25 sliding carriage 34. As shown in the drawings, particularly in Fig. 16, the rotary cutter 47 and its shaft 44 are mounted obliquely across the carriage, its axis of rotation not being at right angles with the sides thereof.

25 The pulley 45 is secured to one end of the shaft 44 and the rotary cutter is driven by the belt 46, which passes around said pulley 45 and under the idlers 38 39, which are mounted on studs in the bracket 37. A tool-stand support 30 35 40 port 49, having extended arms 50 and a bracket 51, is adjustably secured to the carriage 34 by screw-pivot 53 and is provided with slots 54 in the outer ends of the arms 50, which permit of the adjustment of said support, and the set-screw 52, passing through the bracket 51, is adapted to hold said support firmly in the position desired. To the tool-stand support is secured the tool or knife carrying table 55, which in the drawing is 45 50 55 represented as carrying the tools or knives 56 57 58 60. The knives 60 are carried by the bracket 59 on the tool-carrying table 55. The quill F (shown in Fig. 7) shows the parts f' f' f'' f'' f'' f'', which are cut by the respective 55 60 65 knives 56, 57, 60, and 58. The block D while being shaped or turned into the quill F is held steady by the lever 62, which is provided with fingers 62^a and which is secured on the arm 61, which is fixed to the bracket 59, and by 60 65 70 the lever 65, which is pivoted on pin 64 in the arm 63 and is pressed down by spring 67, so that the outer end 68 of the lever 65 passes over and behind the quill. When the carriage 34 moves outwardly, the lever 65 and the lever 62 withdraw the finished quill when it is released from the spindles 45. The arm 69, which is secured to the carriage 34, carries a table 70, which is provided with a cut-out portion 71.

65 66 is a stop for lever 65. A pin 72 is secured to the arm 69. The hopper 75 is secured to the rails 73 and 74. A spring-pressed holder 78 is secured to the pin 77, which is mounted in the bracket 76, and said holder is 70 75 80 85 90 95 100 105 110 115 120 125 130 135 140 145 150 155 160 165 170 175 180 185 made both in construction and arrangement without departing from the essential spirit and scope of my invention.

With this description of my invention, what

5 I claim is—

1. The combination of the frame, and a hopper, having a downwardly-extending spring-pressed holder, with a reciprocating carriage, arms connected with said carriage to receive, 10 release and carry the lowermost block from engagement of said holder, a table, secured to and moving with said carriage to pass under and act as a temporary support for the remaining contents of the hopper, and means 15 for reciprocating said carriage, substantially as set forth.

2. The frame, rotating holding-spindles mounted thereon, one spindle being movable lengthwise, and a hopper having a downwardly-extending spring-pressed holder, in combination with a carriage mounted to reciprocate on said frame, arms pivotally connected to said reciprocating carriage and adapted to release the lowermost block in the 20 hopper from the engagement of the spring-pressed holder, and convey it to the said rotating holding-spindles, a table secured to the rear portion of the said carriage and adapted to follow the block leaving the hopper, and 25 to form a temporary support for the remaining contents of the hopper, means for rotating the holding-spindles, means for communicating to one of the said spindles an intermittent longitudinal movement, and means 30 for imparting a reciprocating movement to the said carriage, substantially as set forth.

3. In a wood-turning machine, the combination with the frame, having a hopper located thereon, of a reciprocating carriage, 40 curved lever-arms having an angular upper extremity and pivotally secured to the said carriage at their lower ends, means pivotally connecting said curved lever-arms to the frame, and a stop to limit the downward movement of the said curved lever-arms, substantially as set forth.

4. In a wood-turning machine, the combination with the frame, a reciprocating carriage mounted to slide thereon, and adjustable bearings secured to said carriage, of a shaft located obliquely across said carriage and journaled in said adjustable bearings, a rotating cutter provided with knives mounted on said shaft, an adjustable support pivotally secured to said carriage, a knife-carrying table secured to said support, and means

carried by said table to bear upon the upper and rear face of the block while being operated upon, substantially as set forth.

5. In a wood-turning machine, the combination with the frame, a reciprocated carriage mounted to slide thereon, and adjustable bearings secured to said carriage, of a shaft located obliquely across said carriage and journaled in said adjustable bearings, a 60 rotating cutter provided with knives mounted on said shaft, an adjustable support pivotally secured to said carriage, a knife-carrying table secured to said support, and means carried by said table to bear upon the upper and 65 rear face of the block while being operated upon, a hopper secured to the frame, a downward-extending spring-pressed holder pivotally secured to said hopper, a table carried by the rear portion of said reciprocating carriage 70 having a portion cut out to permit it to pass on either side of said spring-pressed holder, and to admit the angle-shaped upper extremities of two curved lever-arms to receive the block from the hopper and carry it to 75 rotating holding-spindles, such curved lever-arms, pivotally secured at their lower ends to the said carriage, rotating spindles carried by the frame and adapted to engage, hold and turn said block, one of said spindles being 80 capable of both a longitudinal and a rotary movement, a driving-shaft journaled in the main frame, operative connections between said shaft and the sliding carriage, and operative connections between the said shaft 85 and the longitudinally-moving spindle, substantially as set forth.

6. The combination with the frame, hopper and its spring-pressed holder, and rotating holding-spindles journaled in fixed bearings 90 on said frame, of a reciprocating carriage carrying means for feeding the work to said spindles, revolving cutters and fixed knives, in adjustable supports, and means for discharging the work when completed, and suitable 95 means for reciprocating said carriage to feed the work to the said spindles upon its forward movement and to bring the cutter and knives to the spindles upon its return movement, substantially as set forth.

105 In testimony whereof I affix my signature in presence of two witnesses.

ROBERT W. BARKER.
